(57) **CLAIM**

The ornamental design for a wall outlet, as shown and described.

DESCRIPTION

FIG. 1 is a perspective view of a faceplate and connector module cover for our design for wall outlet;

FIG. 2 is a side elevational view taken from the left side of the top plan view thereof, the opposite-side elevational view being the same as the left-hand side;

FIG. 3 is a top plan view thereof;

FIGS. 4 and 5 are end elevational views as viewed from the bottom and top of FIG. 3, respectively;

FIG. 6 is a perspective view of another embodiment of faceplate and connector module cover for our design for wall outlet;

FIG. 7 is a side elevational view as viewed from the right-hand side thereof, the opposing side being the same;

FIG. 8 is a top plan view thereof;

FIGS. 9 and 10 are end elevational views as viewed from the bottom and top of FIG. 8, respectively;

FIG. 11 is a perspective view of the embodiment of faceplate and connector module cover for our design of wall outlet;

FIG. 12 is a top plan view thereof;

FIG. 13 and 14 are side and end elevational views, respectively as viewed from the side and top of FIG. 12, the opposing end and side being the same;

FIG. 15 is a perspective view of still another faceplate and connector module cover for our design for wall outlet;

FIG. 17 is a top plan view thereof;

FIG. 16 and 18 are side and end elevational views, respectively as viewed from the side and bottom of FIG. 17, the opposing end and side being the same;

FIG. 19 is a perspective view of still another embodiment of a faceplate and connector module cover for our design for wall outlet;

FIG. 21 is a top plan view thereof;

FIGS. 20 and 22 are side and end elevational views, respectively as viewed from the side and bottom of FIG. 21, the opposing end and side being the same;

FIG. 23 is a perspective view of a still further embodiment of a faceplate and connector module cover for our design for wall outlet;

FIG. 24 is a top plan view thereof; and,

FIGS. 25 and 26 are side and end elevational views, respectively as viewed from the side and bottom of FIG. 24, the opposing end and side being the same.
